Fig. 5

Fig. 6

FIG. 1 is a top plan view of a rotor for transistorized ignition in a vehicle engine showing our new design for use for clockwise rotation;

FIG. 2 is a bottom plan view of the device shown in FIG. 1;

FIG. 3 is an elevational view of the device shown in FIG. 1;

FIG. 4 is a top view of a modification of the device shown in FIG. 1, for use for counterclockwise rotation;

FIG. 5 is a bottom plan view of the device shown in FIG. 4; and

FIG. 6 is an elevational view of the device shown in FIG. 4.

We claim:

The ornamental design for a rotor for transistorized

ignition in a vehicle engine, substantially as shown and described.
